UNITED STATES PATENT OFFICE

CHARLES J. ELLIS, OF HAMILTON COUNTY, OHIO, ASSIGNOR TO THE CINCINNATI CAR CORPORATION, OF CINCINNATI, OHIO, A CORPORATION OF OHIO

RAIL BRAKE FOR RAILWAY CARS

Application filed August 5, 1926. Serial No. 127,424.

This invention relates to rail brakes for railway cars, more particularly the type known as electrically operated cars where an electric motor is employed.

5 This invention is kindred to that set forth in the application of Thomas Elliott, Serial No. 127,452 filed on the fifth day of August, 1926, in so far as concerns the general feature of suspending the rail brake shoes a 10 safe distance from the rails, then re-positioning them to a point where they are within a magnetic field established between the shoes and the rails by magnetizing the shoes and then magnetically drawing and 15 applying the shoes to and against the rails, but differs from said other invention in the means for and the mode of positioning the shoes to a point within the magnetic field which I do by wholly mechanical means 20 positive in character.

In other words, the present invention is directed to the organization of a present well-known type of wheel brake operating mechanism consisting of levers, connecting 25 rods and a pneumatic motor or engine, in a new relation by which such mechanism is combined with mechanical devices by which the rail brakes are held a safe distance above the rails and are mechanically lowered into 30 contact with the rails and returned to normal position at a safe distance above them.

The details of this arrangement will be fully set forth in the following specification.

35 In the accompanying drawings,

Figure 1 is in the nature of a diagrammatic view showing in outline two railway car trucks combined with a conventional type of wheel brake operating mechanism 40 including a pneumatic motor;

Figure 2 is a side elevation, on an enlarged scale, of a railway truck equipped with such wheel brake operating mechanism together with one form of my devices 45 combined with such conventional operating mechanism and with a rail brake for positioning the rail shoes;

Figure 2A is a detail view of the actuating rod, its sleeve and part of the live brake 50 lever;

Figure 3 is a side elevation partly in section on line 3—3 of Figure 5 and similar to Figure 2 except showing the parts in the position occupied when the rail brakes have been adjusted from their normal position 55 to that of contact with the rails, during which transition from position to position the rail brakes have been magnetized and brought within magnetic relation to the rails;

Figure 4 is a plan view of my rail brake positioning devices;

Figure 5 is a partial elevation and partial sectional view of the devices shown in 65 Figure 4;

Figure 6 is a longitudinal vertical section of the rail shoe housing with the magnets for magnetizing the housing and shoes; and

Figure 7 is a vertical transverse sectional 70 view of the housing and shoes taken on the line 7—7 of Figure 6.

Referring first to Figure 1, the diagrammatic view, I would state that the numerals 1 and 2 designate two railway car trucks 75 comprising, generally speaking, wheels 3 and side frames 4 mounted to ride on the wheel axles.

To the transoms 5 I pivot what are known as dead brake levers 6 and 7 which depend 80 and carry wheel brake-shoes 8 and 8^a. These levers are connected by links 9, respectively, to live brake levers 10 and 11, which carry wheel brake-shoes 12 and 12^a.

When the usual brake air valve is positioned by the operator to admit air under pressure to the air cylinder 13 through a pipe line 14, its piston 15 will be operated in one direction, while its return movement, when the valve is positioned to permit of the air exhausting, will be effected in the other direction by the spring 16. The former movement causes the piston through its rod 17 to actuate the primary levers 18 and 19 to cause, through connecting rods 18^a and 19^a, the live brake levers 10 and 11 to be actuated to bring their wheel brake shoes 12 and 12^a in contact with the wheels; at 95 which time also the connecting rods 9, 9 will in turn actuate the dead brake levers 100

6 and 7 to cause them to position against the wheels their brake-shoes 8 and 8^a.

The primary levers 18 and 19 are interconnected by a rod 20 while the primary lever 18 is pivoted to the stationary cylinder 13 at the point 21 to afford a fixed fulcrum for this primary lever.

Thus a movement by the pneumatic motor of the primary lever 19 will cause resulting movements of both sets of live brake levers 10 and dead brake levers 11 and 7 of one truck and 6 and 10 of the other truck, resulting in positioning the wheel brake-shoes against the wheels to effect a braking action.

What we have so far described is in general use, and therefore, well known.

Applying my rail brake positioning devices to this conventional wheel brake mechanism attention is called particularly to Figures 2, 3, and 4. It will there be seen that I connect with the live brake lever 10 (and likewise the live brake lever 11) an actuating rod 22 through a sleeve 23 having a stud 24 which passes through the lever 10 and is retained by a nut 25 as best seen in Figure 2A. I place a spring 26 between a nut 27 and the sleeve 23, and below the sleeve I mount on the rod a nut 28, when movement of the lever 10, to the right as viewed in Figure 2, will cause a pull on the actuating rod through the pressure of the sleeve 23 against the spring 26, whose tension may be adjusted by the nut 27, which causes the rod to actuate a bell crank lever 29. This lever is pivoted at 30 to a bracket 31 secured to the transom 5^a. One end of the bell crank lever is attached by the pin 32 to the lower end of the actuating rod 22, while the other end is attached by the pin 33 to the housing 34 within which magnets 35 are placed for magnetizing the side plates 36 of the housing, and thence the rail shoes 37 for the purpose and in the manner hereinafter to be stated.

The movement of the live brake lever 10 from the position shown in Figure 2, in which the magnet housing 34 and the rail shoes are elevated to a safe position for the shoes above the track rails, to the position of that lever shown in Figure 3, causes a lifting action on the actuating rod 22 which results in operating the bell crank lever 29 to depress the housing 34 and the shoes 37 from their normal position to their magnetic position or that in which the shoes are within the magnetic field set up between the shoes and the rails when the shoes are magnetized in the manner to be stated. In the described movement of the lever 10 from the position shown in Figure 2 to that shown in Figure 3 the spring 26 functions to exert a lifting or pulling pressure on the actuating rod 22. On the reverse movement of the lever 10 the sleeve 23 presses against the nut 28 and causes a reverse movement of the

actuating rod to operate the bell crank lever 29 to cause it to permit the housing 34 and the rail shoes 37 to return to normal position under the lifting effect of the suspending springs 38 and 39. These springs are connected at their upper ends through bolts 40 with plates 41 carried by the transoms 5 and 5^a; while the lower ends of the springs are anchored through bolts 42 to the casing 34 and the rail shoes 37. A cross strap 43 extends from each shoe 37 to the other, one strap at each end of the shoes, and the anchors 42 connect with these straps. Bolts 44 connect the ends of the side plates 36 of the housing 34 to the shoes. In this manner the suspending springs 38 and 39, surrounding the sleeves 38^a and 39^a respectively yieldingly support the housing 34 and the rail shoes 37, so that the housing and the shoes may be sustained by these springs 38 and 39 in a position safe for the shoes with respect to the rails and yet permit of the actuating rod 22 and the bell crank lever 29 positioning downward the housing and the shoes within the magnetic field created between the shoes and the rails to the shoes to be magnetically snapped or brought into quick and forcible contact with the rails to effect a rail-braking action.

I will now refer to the structure within the housing 34 and to the construction of the housing itself. It comprises two side plates 36 with a band 46 enclosing the space between the side plates. Bolts 47 connect the side plates and form cores for magnets 35. The wire windings enter into the construction of these magnets having termini 49 leading to a ground connection 50 leading to the controlling circuit, so that these magnets may be energized by any appropriate switch to close the circuit, such, for instance, as shown in the application of Thomas Elliott, Serial No. 127,452 filed on the fifth day of August, 1926.

By preference I fill the casing with an insulating material, as a mixture of wax poured into the casing in a melted state, as indicated at 51 in Figure 6. The circuit may be opened by a separate means under the control of the operator. Any convenient means of circuit-control may be used. After the circuit has been opened the brake shoe leaves the track, due to the operation of the springs.

One of the side plates 36 is provided with a flange 57 adapted to slide in a guide or way 58 formed on the side frame of the truck, generally indicated at 59, so that the housing may be adjusted up and down by the mechanism above described to position it and the attached rail shoes 37.

From the foregoing description it will now be seen, first, that I have combined the conventional wheel brake operating mechanism illustrated in Figure 1 with rail-brake

positioning-mechanism comprised, in the present exemplification best shown in Figures 2 and 3, of the actuating rod and bell crank lever and the spring suspension devices, connected with the rail shoes and supporting electromagnets to magnetize such shoes; and secondly, that I have devised a rail-brake suspending and actuating mechanism consisting, generally, of a casing containing electromagnets, rail brake-shoes adapted to be magnetized by said magnets, springs which normally position the shoes above the rails but yield to positioning them within the magnetic field created between the shoes and rails when the shoes are magnetized, and an actuating rod or device operatively connected with the housing through the intervention of the bell crank lever.

By means of the combination above set forth, and by the use of said suspending and actuating mechanism, I am enabled to apply the wheel brakes and the rail brakes substantially simultaneously and to release said brakes likewise substantially simultaneously; and also by such suspending and actuating mechanism for the rail brakes I am enabled to maintain the rail brakes at a safe distance from the rails while the wheel brakes are out of contact with the wheels and to position the rail brakes within the magnetic field between them and the rails to bring about their magnetic movement to and against the rails concurrently with the application of the wheel brakes to the wheels.

These operations and the organization and mechanism by which they are accomplished are highly useful and fully effective in the safe and quick braking of railway cars.

It will be understood that I desire to comprehend within my invention such modifications as may be necessary to adapt it to varying conditions and uses.

Having thus fully described my invention, what I claim as new and desire to secure by Letters Patent, is:

1. In railway brakes, the combination with wheel brakes and operating mechanism therefor, of rail brakes, magnets to magnetize them, yielding suspension devices to support the rail brakes safely remote from the rails and permit positioning them within the magnetic field between them and the rails, and actuating devices connected with the wheel-brake operating-mechanism to cause the actuating devices to position the rail brakes within said magnetic field.

2. In railway brakes, the combination with wheel brakes and operating-mechanism therefor comprising levers, connecting rods and an operating motor, of rail brakes comprising rail shoes, magnets associated therewith, spring suspension devices and actuating mechanism connected to the rail brakes and to one of said levers whereby movement

of the several levers will effect a movement also of the rail brakes to a position within a magnetic field between said rail brakes and the rail.

3. In railway brakes, the combination with wheel brakes, dead levers, live levers, connecting links between said levers, connecting rods and actuating levers, and a pneumatic motor to operate said mechanism, of rail brakes, associated magnets, spring suspension devices adapted to carry the same, and actuating devices comprising rods connected to and operated by the live levers, and bell crank levers connected to said rods and to the brake shoes, whereby the brake shoes are positioned within a magnetic field between them and the rails when the dead levers and live levers apply the wheel brakes to the wheels.

4. In railway brakes, the combination with two trucks, each carrying interconnected dead and live levers and each lever a wheel brake shoe, operating levers connected to the live levers and a pneumatic engine connected to actuate said operating levers to apply the wheel brakes to the wheels of the two trucks, of rail brakes, a housing connected therewith, electromagnets carried by the housing, suspending springs connected to the trucks and to the housing, bell crank levers connected to the housing and actuating rods to the bell crank levers and to the live levers, whereby when the pneumatic engine actuates the wheel brakes it will also actuate the rail brakes to adjust them from their normal position safely remote from the rails to a position within a magnetic field between the rail shoes and the rails, said magnets being operative to magnetize the rail shoes.

5. In railway brakes, the combination with a truck and wheel-brake levers and shoes, of rail brakes, associated electromagnets, yielding suspension devices to support the rail brakes, and an actuating device connected to one of the wheel brake levers and connected to the rail brakes to position them within a magnetic field between them and the rails when said wheel-brake lever is actuated.

6. In railway brakes, the combination with a truck, of a rail brake comprising a shoe, associated electromagnets to magnetize the shoe, spring suspension devices to support the shoe normally a safe distance from the rail, an actuating rod and a bell crank lever connected to it and to the rail shoe to position the latter within a magnetic field between it and the rail.

7. In railway brakes, the combination with a truck of a housing, electromagnets carried thereby, rail brake shoes, spring suspension devices connected to the truck and adapted to suspend the housing and rail shoes safely above the rail and to permit

positioning the shoes within a magnetic field between them and the rails, a bell crank lever connected to the housing and an actuating rod also connected to the bell crank lever, whereby when said rod is actuated it will position the shoes within such magnetic field.

8. In railway brakes, the combination with a truck and a wheel brake lever, of a housing, a rail brake comprising a rail shoe, spring suspension devices adapted to support the rail shoe and the housing, a bell crank lever connected to the housing and an actuating rod connected to the bell crank lever, and having a sliding connection with said wheel brake lever, the rail shoe being normally supported at a safely remote distance from the rail.

9. In railway brakes, the combination with a truck, a bracket secured thereto, a bell crank lever mounted on said bracket, an electromagnet housing connected to said lever, an electromagnet within the housing, an actuating rod also connected to said lever, spring suspension devices connected to the truck and to said housing and rail brake shoes also connected to said spring suspension devices, the suspension devices supporting the brake shoes normally at a safely remote distance from the rails, the brake shoes being positioned within a magnetic field between them and the rails upon actuation of the lever.

10. In railway brakes, the combination with a wheel brake lever, of an actuating rod for a rail brake, said rod being slidably connected with said lever, a spring on said rod to effect a yielding connection between it and the lever when the lever moves in one direction and a stop on the rod to effect a positive connection between the rod and lever when the lever moves in the other direction.

In testimony whereof, I affix my signature.
CHARLES J. ELLIS.
